TROPHY BASE

Josephine M. Richardson, R.R. 5, Decatur Hi-Way
Airport, Decatur, Ind.

Filed Apr. 30, 1963, Ser. No. 74,680

Term of patent 14 years

(Cl. D29—28)

Fig.-3

Fig.-1

Fig.-2

FIGURE 1 is a front elevational view of a trophy base showing my new design, the back of the pedestal portion is plain and the upper portion thereof is substantially a mirror image of the front;

FIGURE 2 is a side elevational view thereof, the side opposite thereto being substantially a mirror image thereof; and

FIGURE 3 is a top plan view thereof.

The uppermost structure of the trophy base is in the form of a hollow transparent housing.

I claim:

The ornamental design for a trophy base, as shown and described.
